2,541,389

EXPLOSIVE COMPOSITION CONTAINING
POLYBUTENE

William J. Taylor, Tamaqua, Pa., assignor to
Atlas Powder Company, Wilmington, Del., a
corporation of Delaware

No Drawing. Application October 28, 1949,
Serial No. 124,239

14 Claims. (Cl. 52—5)

1 The present application relates to a novel explosive and more particularly it relates to a dynamite possessing desirable characteristics.

An object of the present invention is the provision of a dynamite which is readily packed into cartridges and is not subject to sifting out of cartridges containing it.

Another object of the invention is the provision of a dynamite which holds its shape and is not free-running.

A further object of the invention is a provision of a dynamite which is cohesive.

Other objects of the invention will be apparent from the following description.

Some dynamites contain relatively high proportions of liquid ingredients mixed with granular ingredients. Nitroglycerine, for example, is a common liquid ingredient in dynamites. Dynamites containing a high proportion of liquid ingredients are more or less plastic and cohesive. Particularly is this true of dynamites containing nitroglycerine gelatinized with nitro cellulose. This cohesiveness and plasticity is a valuable characteristic of such dynamites. It makes them easy to pack into cartridges and it prevents their sifting from cartridges in which they are packed. In addition, cartridges containing such dynamites can be cut without incurring loss and hazard due to spillage of explosive.

However, for many uses, it is not desirable that dynamites contain high proportions of liquid ingredients. Many nitroglycerine dynamites, for example, are prepared with amounts of nitroglycerine below 20%. Such dynamites and others containing low proportions of liquids contain a high proportion of dry powdered or granular ingredients. Relatively dry dynamites suffer from lack of cohesiveness. They are difficult to pack in cartridges; they tend to sift out of cartridges in which they are packed, and cartridges containing them cannot readily be cut without spilling the dynamite. Furthermore, such dynamites are difficult to load into upwardly pitching bore holes when the shells have been slit to make the cartridges easily compacted.

By means of the present invention, powdery granular dynamites, such as those just described, may be prepared in cohesive form so that they have the desirable properties of the more plastic types of dynamites.

According to the present invention, there is included, with the usual ingredients of a dyna-

2 mite which is normally noncohesive, a viscous liquid polybutene product selected from the group consisting of a viscous liquid polybutene, preferably a liquid polybutene possessing tackiness, and a tacky solution of a solid rubbery polymer in a liquid polybutene. Polybutene is also known as polymerized butene, polymerized isobutylene, or polyisobutylene. The solid rubbery polymer dissolved in the liquid polybutene

5 may be any of a variety of solid, plastic, or rubber-like materials, and solid rubbery polybutene, natural rubber, or a synthetic rubber soluble in the polybutene may be given as examples. Since the polymers dissolved in the

10 polybutene are solid and rubbery or plastic, they are of relatively high molecular weight.

The viscous liquid product, although present in a small amount, is effective in converting the relatively free-flowing explosive composition into

15 a cohesive product and tests have shown the sticky liquid product, when present in the explosive composition as described herein, does not deleteriously affect the explosive properties of compositions containing it. Thus, the sensitivity and velocity of the composition is not appreciably affected by the presence of the product in the composition.

The viscosity and stickiness or tackiness of polybutene depends on the degree of polymerization thereof as indicated by the molecular weight of the product, and polybutene, as do most polymeric materials, progresses from a liquid of relatively low viscosity and tackiness through a liquid product of relatively high viscosity and characterized by a greater degree of tackiness

20 to a plastic or rubber-like solid, as the degree of polymerization of the product increases. When reference is made herein to molecular weight, it is to be understood that the term means the average molecular weight of the product since a polymerized product usually contains polymers of both higher and lower molecular weights than the average molecular weight. The molecular weights of the solid rubbery polybutene materials set forth herein were determined

25 by the Staudinger method using the relation:

$$\text{Molecular weight} = \frac{\text{intrinsic viscosity}}{0.0000318}$$

30 The liquid polybutenes are conveniently identified according to their viscosities determined with the Saybolt Universal viscosimeter and the

viscosities hereinafter set forth are expressed as SSU (seconds Saybolt Universal), the temperature of the liquid used in the determination of viscosity being 210° F. for the more viscous liquids and 100° F. for the less viscous liquids. Liquids whose viscosity at 210° F. is below 50 SSU are measured at 100° F., and in the case of the liquid polybutenes, a viscosity of 50 SSU (210° F.) corresponds to approximately 350 SSU (100° F.).

When the liquid product employed in the dynamite composition is a polybutene per se, the viscosity thereof may vary over a wide range but advantageously it will have a viscosity of at least approximately 180 SSU (100° F.) and preferably the polybutene will have been polymerized to the stage where the product itself is a liquid of relatively high viscosity and possesses tackiness. It has been found that a polybutene having a viscosity from about 180 SSU (100° F.) to about 2700 SSU (210° F.), and preferably from about 135 SSU (210° F.) to about 620 SSU (210° F.), will possess especially desirable properties so that it will impart high cohesiveness to a relatively free flowing dynamite composition. Thus, when the polybutene has a viscosity of at least approximately 135 SSU (210° F.), it will possess tackiness which aids in imparting the desirable properties to a free flowing dynamite composition. When the viscosity is above about 620 SSU (210° F.), the polybutene will be of relatively high viscosity at normal atmospheric temperatures and it may be desirable to warm it to reduce the viscosity before it is mixed with the dynamite ingredients.

In the preferred embodiment of the invention where the tacky liquid product comprises a solution of a solid, rubbery polymer in a liquid polybutene, the liquid polybutene employed will have been polymerized only to a relatively low degree where it will be a liquid of relatively low viscosity, for example, the polybutene will advantageously have a viscosity between about 50 SSU (100° F.) and about 620 SSU (210° F.), preferably between about 100 SSU (100° F.) and about 300 SSU (210° F.). Specific examples of polybutenes are products having viscosities of 52, 154, and 222 SSU (210° F.). As indicated above, the desired tackiness and viscosity is imparted to the liquid polybutene of relatively low molecular weight by dissolving therein a solid, rubber-like polymer, that is a high molecular weight polymer that is soluble in the liquid polybutene. While, as stated, the solid rubbery polymer may be of a variety of polymeric materials, advantageously the solid, rubber-like polymer is a polybutene or natural rubber. When the solid rubber-like polymer is polybutene, it may be any polybutene product having such properties, and generally the molecular weight of the polybutene will be between about 40,000 and about 120,000, although solid polymers of lower or higher molecular weight may be used if desired, particularly satisfactory results being obtained when a polybutene having a molecular weight in the neighborhood of 80,000 is used.

The percentage of the solid rubber-like polymer dissolved in the liquid polybutene of relatively low molecular weight may be varied as desired to provide a viscous tacky liquid and generally, between about 1% and about 10% of the solid rubbery polymer will be dissolved in the polybutene. The amount dissolved in any particular case will depend upon the molecular weight of the liquid polybutene and of the solid rubbery polymer and upon the viscosity and tack-

iness of the solution desired. Even though the resulting solution may have a viscosity corresponding to that of a liquid polybutene per se, the solution will be characterized by a greater tackiness and it is for this reason that the use of the described solution is preferred. In preparing the solution, it may be necessary to heat the mixture of the liquid polybutene and the solid polymer and, as in the case of a liquid polybutene per se, the solution if desired may be warmed to reduce its viscosity before mixing it with the dynamite ingredients.

The following are examples of solutions that have been used in explosive compositions which are relatively free-flowing to impart cohesiveness thereto:

Solution A

2 1/2 parts of a solid, rubber-like polybutene having a molecular weight of about 80,000 were 20 dissolved in 60 parts of a liquid polybutene having a viscosity of about 222 SSU (210° F.). The solution was viscous and very tacky.

Solution B

25 A solution was prepared containing 6% of the high molecular weight polybutene used in the preparation of Solution A in a liquid polybutene having a viscosity of about 154 SSU (210° F.). The solution was very tacky but not so viscous 30 as Solution A.

Solution C

A solution was prepared containing 7 1/2% of the high molecular weight polymer used in the preparation of Solution A, the remainder being the liquid polybutene used in the preparation of Solution B. The solution was tacky and slightly more viscous than Solution B. This is now the preferred solution.

Solution D

40 A solution was prepared containing 6% of the high molecular weight polymer used in the preparation of Solution A dissolved in a liquid polybutene of a viscosity of about 52 SSU (210° F.). 45 The solution was characterized by excellent tackiness but was less viscous than Solution B.

Solution E

50 A solution was prepared containing 7 1/2% of the high molecular weight polymer used in the preparation of Solution A dissolved in a liquid polybutene of a viscosity of about 52 SSU (210° F.). The solution was very tacky and was slightly more viscous than Solution D.

Solution F

55 A solution was prepared containing 4% of a solid rubbery polybutene having a molecular weight of about 100,000 in a liquid polybutene of a viscosity of about 52 SSU (210° F.). The solution was characterized by a fairly high viscosity and by good tackiness.

Solution G

60 A solution was prepared which corresponded to Solution F except that the solid rubbery polymer had a molecular weight of about 120,000. The resulting solution was slightly more viscous and tacky than Solution F.

Solution H

65 4 parts of natural rubber (smoked sheet) were dissolved in 96 parts of a liquid polybutene having a viscosity of about 222 SSU (210° F.). The resulting solution was tacky and viscous.

Solution I

A solution was prepared like Solution H except that para rubber was used in place of the smoked sheet. A solution of comparable properties was obtained.

Solution J

A solution of 3% smoked sheet rubber was dissolved in a liquid polybutene having a viscosity of about 222 SSU (210° F.). The solution was slightly less viscous than Solution H but possessed good tackiness.

Solution K

A solution of 2% smoked sheet rubber was dissolved in a liquid polybutene having a viscosity of about 222 SSU (210° F.). The solution was slightly less tacky and viscous than Solution J.

The amount of the tacky liquid, whether it be the liquid polybutene per se or the solution of the solid, rubber polymer in the liquid polybutene mixed with the dynamite ingredients in preparing the cohesive product of the invention, will depend upon the cohesiveness desired in the explosive. In general, amounts of the tacky liquid as low as 0.2% based on the weight of the explosive are found to produce desirable improvements in cohesiveness. On the other hand, amounts above about 5% based on the weight of the explosive do not usually produce much increased beneficial effects, although amounts above that figure may be used if desired, provided, of course, that the amount employed does not deleteriously affect the desired properties of the explosive. Preferably, the amount of the tacky liquid employed will be between about 0.5% and about 2%.

As has been stated, the invention is applicable for use in connection with any of the types of dynamite that tend to sift or are loose or free-running to convert the dynamite into a product which will hold its shape. As is well known, dynamites contain, in addition to an explosive sensitizer, one or more oxidizing salts and one or more fuels, such as wood pulp, coal, apricot pit pulp, bagasse, corn flour, sulphur, or the like, which serve also as absorbents or adsorbents for the liquid sensitizers; the proportion of oxidizing salts to fuel being such that the oxygen balance of the explosive, exclusive of the wrapper, generally will lie between about -35% and about +10%, usually between about -4% and about +10%. For a discussion of the oxygen balances of explosives, see Bureau of Mines Bulletin 219 (1923), pp. 102-105. Examples of sensitizers are nitroglycerine, or nitro-aromatics like trinitrotoluene, dinitrotoluene, and mononitrotoluene, with or without highly combustible powders such as aluminum dust. The term "nitroglycerine" includes the various mixtures commonly called nitroglycerine in the explosive industry, common ingredients of such mixtures, other than nitroglycerine, being nitroglycerol, nitro sugars, and nitrates of higher polyhydric alcohols. Other dynamite ingredients such as, for example, antacid materials, like calcium carbonate, may be, and usually are, also included.

In general, it may be said that the practical utility of the invention is diminished in formulations having in excess of about 20% of liquid ingredients. Such formulations are usually sufficiently cohesive as not to require the assistance of the present invention. Advantageously, the sensitizer will be a liquid explosive sensitizer, preferably nitroglycerine.

The tacky liquid used in accordance with the present invention is itself a fuel. Consequently,

if an explosive of proper oxygen balance is to be prepared, the fuel characteristics of the tacky liquid should be considered and normally the tacky liquid will replace part of the fuel which would otherwise be present. The oxygen value of the polybutene products used herein will be about -3.4.

While the liquid polybutene product described herein may be used, as stated, to impart cohesiveness to any dynamite lacking in such property or the desired degree thereof, it is particularly applicable for use in high and low density ammonia and straight dynamites, particularly dynamites where the explosive sensitizer is between about 15 2-3% and about 20%, usually between about 5% and 15%. For use in small diameters, with direct initiation by a cap, at least about 5% of the explosive sensitizer is generally used, whereas in large diameter cored explosives, as little as about 2-3% of the sensitizer may be employed. In the ammonia dynamites, the granular ammonium nitrate is usually present between about 3% and about 90%, and the liquid explosive sensitizer will generally be employed in an amount within the 20 stated limits. The liquid explosive sensitizer is often nitroglycerine or a solution of a nitro aromatic compound such as trinitrotoluene or dinitrotoluene dissolved therein. The balance of the 25 ammonia dynamite is made up of the usual ingredients such as solid fuels and an oxidizing salt, for example sodium nitrate. These materials are usually present in such proportions that the oxygen balance of the powder, exclusive of wrapper, lies between about -4% and +10%. In straight 30 dynamites, the composition will comprise generally a liquid explosive sensitizer, such as is used in ammonia dynamite, an oxidizing salt other than ammonium nitrate, such as sodium nitrate, solid fuels, and the like. While in a straight dynamite, the sensitizer, for example nitroglycerine, may vary between about 5% and about 60%, the 35 invention as stated is especially applicable for use in dynamite containing not more than about 20%. The oxygen balance of the powder, exclusive of the wrapper, will usually be between about -35% and about +10%, generally between about -4% and about +10%. Usually the solid fuel will be present in an amount between about 3% and about 20% and, as stated, both types of explosives 40 will generally contain an antacid such as calcium carbonate in a small amount, and either way, if desired, contain a gelatinizing agent such as nitrocotton in small amounts. Other ingredients 45 customarily employed in such products may be present, and in any particular dynamite product, the proportions of the ingredients employed will provide an explosive of the desired properties.

In preparing the dynamite of the present invention, the tacky liquid is mixed with the other 50 ingredients in any suitable manner and it is desirable to distribute the liquid throughout the other ingredients.

The invention will be further described by the following specific examples:

Example 1

A dynamite was prepared in the usual manner to the following formula:

	Per cent
Nitroglycerine	6
70 Coarse ammonium nitrate	80.4
Sodium nitrate	5
Wood pulp	2.0
Fine apricot pit pulp	4.1
Yellow corn flour	2.0
Chalk	0.5

This dynamite packed 143.3 1 1/4" x 8" cartridges per 50 pound case. It was a moist moderately cohesive powder. When the cartridges were cut, however, the powder tended to run out, and this powder caused considerable difficulty by sifting out of its shells during transit.

Example 1-A

A dynamite was made up as in Example 1, except that .5% of Solution C was substituted for .5% of yellow corn flour. The resulting dynamite packed 146.8 1 1/4" x 8" cartridges per 50 pound case. It was cohesive and moist and it held its shape when cartridges containing it were unrolled. It packed easily, and there was no sign of sifting.

Example 1-B

Another dynamite was made up as in Example 1 except that 1% of Solution C was substituted for yellow corn flour. This dynamite packed 144.2 1 1/4" x 8" cartridges per 50 pound case and was more cohesive than the dynamite of Example 2.

Example 1-C

A fourth dynamite was made as in Example 1, except that in this case 2% of Solution C was used, replacing all of the corn flour. This dynamite packed 142.7 1 1/4" x 8" cartridges per 50 pound case. It was fully as cohesive as an ordinary semi-gelatin dynamite and exhibited the "crawly" characteristic of semi-gelatin dynamite.

Example 2

A dynamite was prepared in the usual manner to the following formula:

	Per cent
Nitroglycerine	6
Ammonium nitrate	86.50
Ground walnut shells	4.75
Starch	2.25
Chalk	0.50

This powder was only very slightly moist and flowed readily when the cartridge was cut and sifted through the crimps when handled.

A series of explosives were made up using 0.75% of each of Solutions A, B, C, D, E, F, and G in place of the corresponding amount of starch. In all cases, the powder was moist, cohesive, crawly, held its shape when the wrapper was removed, and did not flow when the cartridge was cut. Rough handling of cartridges having partially open crimps produced no sifting.

Example 3

Ammonia dynamites were prepared in the usual manner to the following formulae:

	a	b	c	d	e
Nitroglycerine. Per Cent	6.0	6.0	6.0	6.0	6.0
Coarse Ammonium Nitrate	82.0	83.0	82.0	82.0	82.0
Sodium Nitrate	5.0	5.0	5.0	5.0	5.0
Fine Apricot Pit Pulp. Per Cent	3.5	2.5	3.5	3.5	3.5
Yellow Corn Flour	do	1.0	2.0	2.0	2.0
Chalk	0.5	0.5	0.5	0.5	0.50
Solution H	do	1.0	2.0	do	do
Solution I	do	do	1.0	do	do
Solution J	do	do	do	1.0	do
Solution K	do	do	do	do	1.0

All of the above dynamites were moist, cohesive, crawly, and showed no tendency to sift through a partially open crimp. These properties are to be contrasted to the same explosive compositions

not containing any of the solutions and in which the yellow corn flour was correspondingly increased, which was only slightly moist, barely cohesive, flowed readily when the cartridge was cut, and sifted through the crimps when handled.

Example 4

Ammonia dynamites were prepared in the usual manner to the following formulae:

		a	b	c	d
15	Nitroglycerine. Per Cent	6.0	6.0	6.0	6.0
	Coated Ammonium Nitrate. do	81.1	82.6	82.6	82.6
	Sodium Nitrate. do	4.3	4.4	4.4	4.4
	Wood Pulp. do	2.0	2.0	2.0	2.0
	Fine Apricot Pit Pulp. do	4.1	3.5	3.5	3.5
	Yellow Corn Flour. do	2.0	do	do	do
	Chalk. do	0.5	0.5	0.5	0.5
20	Liquid Polybutene per se.	11.0	21.0	21.0	21.0

¹ Viscosity of about 155 SSU (210° F.).

² Viscosity of about 220 SSU (210° F.).

³ Viscosity of about 2700 SSU (210° F.).

25 The dynamite of Example 4 (a), which contained no polybutene product, was slightly moist and fairly free-running, whereas the explosives of Examples 4 (b), (c), and (d) were moist and were not free-running. The explosive of Example 4 (b) was fairly cohesive, whereas the explosives of Examples 4 (c) and 4 (d) were slightly tacky and were characterized by cohesiveness.

Example 5

Straight dynamites were prepared in the usual manner to the following formulae:

	a	b	c	d
40	Per cent	Per cent	Per cent	Per cent
	Nitroglycerine. 5.0	5.0	5.0	5.0
	Coarse Sodium Nitrate. 62.0	62.0	62.0	62.0
	Coarse Sulphur. 22.0	22.0	22.0	22.0
	Coarse Apricot Pit Pulp. 10.0	10.0	10.0	10.0
45	Ground Sawdust. do	do	3.0	3.0
	Chalk. 1.0	1.0	1.0	1.0
	Solution C. 1.0	1.0	do	do

50 The dynamites Examples 5 (a) and 5 (c), which contained no polybutene products, were moist, somewhat cohesive but did not extrude readily under pressure, whereas the dynamites of Examples 5 (b) and 5 (d) were moist, cohesive, fairly readily extrudable under pressure, and packed and loaded much better than the explosive of Examples 5 (a) and 5 (c).

Example 6

60 Ammonia dynamites were prepared in the usual manner to the following formulae:

	a	b	c	d
65	Nitroglycerine. 8.80	8.80	8.80	8.80
	Coarse Ammonium Nitrate. 81.20	81.20	81.20	81.20
	Fine Ammonium Nitrate. do	2.50	2.50	2.50
	Yellow Corn Flour. do	4.75	4.25	4.00
	Wood Pulp. do	2.25	2.25	2.25
	Chalk. do	0.50	0.50	0.50
70	Solution C. do	0.50	0.75	1.00
	Character. (1)	(2)	(3)	(4)

¹ Quite free running.

² Moderately cohesive.

³ Cohesive, slightly crawly.

⁴ Cohesive, crawly, excellent character.

Example 7

Ammonia dynamites were prepared in the usual manner to the following formulae:

	a	b	c	d
Nitroglycerine.....per cent.	10.0	10.0	10.0	10.0
Nitrocotton.....do	0.1	0.1	0.1	
Fine Ammonium Nitrate.....do	77.4	77.4	77.4	77.5
Fine Sodium Nitrate.....do	4.1	4.4	5.0	5.0
Bagasse.....do	2.4	2.6	3.0	3.0
Fine Apricot Pit Pulp.....do	0.8			
Yellow Corn Flour.....do	3.7	3.0	1.5	1.5
Sulphur.....do	0.5	0.5	0.5	0.5
Chalk.....do	1.0	1.0	1.0	1.0
Solution C.....do			1.0	1.5
Character.....	(1)	(2)	(3)	(4)

¹ Moist, moderately cohesive.

² Moist, cohesive, barely crawly.

³ Moist, more cohesive than (b). Slightly crawly. Good body.

⁴ Much like (c) but slightly less crawly.

Considerable modification is possible in the composition of the viscous, tacky liquid employed in the explosive composition as well as in the other ingredients of the composition without departing from the essential features of the invention.

I claim:

1. A dynamite comprising an oxidizing salt in granular form, an explosive sensitizer and a solid fuel, and having mixed therewith a viscous liquid product selected from the group consisting of a liquid viscous polybutene and a liquid viscous solution of a solid rubbery polymer dissolved in a liquid polybutene.

2. The dynamite of claim 1 wherein the viscous liquid product is a liquid viscous polybutene.

3. The dynamite of claim 1 wherein the viscous liquid product is a solution of a solid rubbery polybutene dissolved in a liquid polybutene.

4. The dynamite of claim 1 wherein the viscous liquid product is a solution of natural rubber in a liquid polybutene.

5. A dynamite comprising an oxidizing salt in granular form, a liquid explosive sensitizer, a solid fuel, and a viscous liquid polybutene having a viscosity from about 180 SSU (100° F.) to about 2700 SSU (210° F.) in an amount between about 0.2% and about 5.0% based on the weight of the dynamite composition.

6. The dynamite of claim 5 wherein the viscosity of the viscous liquid polybutene is between about 135 SSU (210° F.) and about 620 SSU (210° F.) and wherein the liquid explosive sensitizer comprises nitroglycerine and is present in an amount less than about 20%.

7. The dynamite of claim 5 wherein the oxidizing salt comprises ammonium nitrate and wherein the liquid explosive sensitizer comprises nitroglycerine.

8. The dynamite of claim 5 wherein the oxidizing salt comprises ammonium nitrate, wherein the liquid explosive sensitizer comprises nitroglycerine and is present in an amount less than about 20% and wherein the viscosity of the viscous liquid polybutene is between about 135 SSU (210° F.) and about 620 SSU (210° F.).

9. A dynamite comprising an oxidizing salt in granular form, a liquid explosive sensitizer, a solid fuel and a tacky liquid comprising a solid rubbery polymer dissolved in liquid polybutene, the tacky liquid product being present in an amount from about 0.2% to about 5.0% based on the weight of the dynamite composition.

10. The dynamite of claim 9 wherein the tacky liquid comprising a solid rubbery polymer dissolved in liquid polybutene contains from about 1% to about 10% of the solid rubbery polymer and wherein the solid rubbery polymer is dissolved in a liquid polybutene having a viscosity between about 50 SSU (100° F.) and about 620 SSU (210° F.).

11. The dynamite of claim 9 wherein the tacky liquid comprising a solid rubbery polymer dissolved in liquid polybutene contains from about 1% to about 10% of the solid rubbery polymer and wherein the solid rubbery polymer is dissolved in a liquid polybutene having a viscosity between about 100 SSU (100° F.) and about 300 SSU (210° F.) and wherein the liquid explosive sensitizer comprises nitroglycerine present in an amount less than about 20%.

12. The dynamite of claim 9 wherein the oxidizing salt comprises ammonium nitrate; wherein the liquid explosive sensitizer comprises nitroglycerine and is present in an amount less than about 20%; and wherein the tacky liquid comprising a solid rubbery polymer dissolved in liquid polybutene contains from about 1% to about 10% of the solid rubbery polymer and wherein the solid rubbery polymer is dissolved in a liquid polybutene having a viscosity between about 50 SSU (100° F.) and about 620 SSU (210° F.).

13. The dynamite of claim 12 wherein the solid rubbery polymer is a solid rubbery polybutene.

14. The dynamite of claim 12 wherein the solid rubbery polymer is natural rubber.
